SOCKET FOR FLUORESCENT LAMPS

George N. Fortin, Pawtucket, R. I.

Application November 18, 1952, Serial No. 321,155

3 Claims. (Cl. 339—53)

My invention relates to sockets for fluorescent lamps having two contact pins and of the type now in commercial use.

In fluorescent lamp sockets now in general use entrance slots for the contact prongs of the fluorescent lamp are generally provided in the lower edge of the lamp socket opening when the lamp socket is mounted. Particularly in industrial installation this type of socket has not proved to be very practical since in this type of installation there is considerable vibration present which tends to dislodge the fluorescent lamp from its socket. This is generally due to the fact that through aging, the contact springs lose their resilience, and eventually vibration dislodges the lamp from the socket, causing it to fall, the prongs readily passing out of the slots that in these prior art sockets generally extend in a downward direction in the socket. To combat this difficulty, various retainer means have been utilized, the most common form of which slips over the end of the lamp socket and closes the slot to prevent the lamp from falling out.

It is, therefore, the main object of my invention to provide a fluorescent lamp socket which will overcome the foregoing difficulties.

Another object of my invention is to provide a fluorescent lamp socket which will not need any external means to hold the fluorescent lamp in the socket.

A further object of my invention is to provide a fluorescent lamp socket of such a construction that should the fluorescent lamp contact pins be dislodged from the spring contact means in the socket, the lamp will remain engaged with the insulating portion of the socket.

A still further object of my invention is the provision of a fluorescent lamp socket which comprises relatively few parts such that it may be easily assembled and manufactured at low cost.

In the drawings:

Figure 1 is a plan view of a tubular discharge lamp supported at each end by lamp sockets constructed in accordance with my invention;

Figure 2 is a front elevation of the lamp socket;

Figure 3 is a rear elevation thereof with the closure plate removed, showing the contact arrangement;

Figure 4 is a sectional view along lines 4—4 of Figure 2, showing the lamp pins in position;

Figure 5 is an edge view taken on lines 5—5 of Figure 2;

Figure 6 is a sectional view taken on lines 6—6 of Figure 3;

Figure 7 is a sectional view taken on lines 7—7 of Figure 3;

Figure 8 is a rear elevational view of the lamp socket with the contact elements removed;

Figures 9 and 10 are perspective views of the contact strips.

In proceeding with my invention, I provide a left and a right housing of insulating material such as molded plastic, cover plates, and two pairs of contact strips. The general shape of the housing is shown by the drawings, the

2

housing being formed with an upright portion extending from a base portion, the base portion serving to mount the socket on a supporting plate such as a reflector in a manner well known to those skilled in the art so that the upper portion will be suspended from the reflector.

Referring to the drawings, I have shown a tubular discharge lamp 11 supported at each end by lamp sockets 12. The lamp 11 may be of a type commonly known to the trade as a fluorescent lamp, in which the filaments are mounted at each end. Electrical connection to the filaments is obtained through spaced contact pins 13, which are mounted in opposite ends of the lamp and which project therefrom, thereby serving as a mounting means. The lamp socket 12 is made up of an upright member 14 and base member 15. The upright member 14 has side walls 14' and an end wall 14" and is provided with a U-shaped recess 16 and a slot 17 communicating therewith. Spring receiving channels 16' extend from the recess 16 separated by a raised portion 18 formed integral with the upright member 14 and the base 15. The upper end of this raised portion 18 is provided with a narrow neck 19, which supports a generally circular guide portion 20 having a diameter of approximately the contact pin spacing of the fluorescent lamp 11.

Disposed in each channel 16' are resilient contact strips 21 and 22. Each of the contact strips 21 and 22 is resilient and provided with an arcuate upper portion 23 and may also be provided with small depressions 24 to engage the contact pins 13 of the fluorescent lamp 11. Contact strip 22 is additionally provided with an up-turned end 25 to assist sliding the contact pin 13 into the depression and contact strip 21 is provided with an extended end closely adjacent but spaced from neck 19 to prevent the contact pin 13 from slipping to the wrong side of the contact.

Each of the contact strips 21 and 22 has a horizontal end 26 which serves as a terminal portion and which is seated in the slots 27, 28 molded into the wall and center portion, respectively. To additionally hold the contact springs in position in the leg portions of the channels 16' a horizontal partition 29 integral with the socket 12 extends from each side wall to within a short distance of the center portion 18. These partitions being placed a predetermined distance from the base form guides for the contact springs 21 and 22, respectively. Each of the horizontal portions 26 of the contact members is provided with a hole 30 to accept a terminal screw, not shown, for the attachment of an electric conductor. To further hold the contact springs in the channels 16', there is additionally provided an insulating plate 31 which is suitably fastened to the back of the upright member by rivets 32 forming a rear wall.

The base 15 which is integral with the upright portion 14 is provided with parallel horizontal slots 33 which provide ducts for the electrical conductors that lead to the terminal portions 26 of the contact strips. A vertical slot 35 is positioned in the center of the base 15 for the reception of an attaching bolt. Positioned along this vertical slot 35 is a groove 36 of a thickness to receive an attaching nut which may be readily slipped therein, the attaching bolt communicating with the threads in this attaching nut and holding the base 15 to the reflector of the fluorescent lamp fixture. To insulate the terminals from the reflector of the fluorescent lamp fixture, a fiber insulating strip, not shown, may be seated in the recesses 37 which are provided in either end of the face.

In mounting a lamp, a pair of sockets is provided, one for each end of the lamp, and these are suspended from a support such as a reflector so that the slots 17 will open in the same direction. The lamp contact prongs 13 are moved horizontally through the slots 17 until one of the contact prongs engages the contact member 21 and rests against the neck portion 19. By merely rotating the lamp, the other contact prong will swing around the

first contact prong and engage the spring contact member 22, sliding therealong until the depression 24 is reached. To release the lamp, it is merely necessary to reverse the process, inasmuch as the edges of the depressions 24 and the contact spring member 22 are sufficiently rounded to permit the contact prongs 13 to slip out thereof. Additionally, the lamp may be inserted in the socket by passing the prongs 13 through the slot 17 and directing one set of prongs upwardly to engage the up-turned portion 25 of the contact spring member 22. The lamp 11 may then be slightly rotated and moved laterally to position the two prongs vertically and in contact with the contact spring members 21 and 22 at the depressions 24 thereof.

It will be seen that by shaping the recess 16 in the manner shown and by providing the entrance slot 17 in the side wall of the lamp socket, accidental removal of the lamp from the socket is practically prevented. Should for instance the contact pin 13 become disengaged with the contact spring 21 and the other pin 13 disengaged with the contact spring 22, the lamp pins will remain retained in the recess 16 and cannot pass out of the slot 17 to cause the lamp to fall from the socket because of its distance above the bottom of the recess 16 being greater than the spacing between contact pins 13. Additionally, it will be noted that the contact pins 13 are disposed in a vertical plane and are urged against the central raised portion 20. In this manner vibration, which normally occurs in a vertical plane, will be partially absorbed by the resilience of the contact springs 21 and 22, thereby further preventing the lamp from being dislodged from the socket.

My invention provides a rugged socket construction for supporting a tubular lamp, which is particularly adapted to industrial installation although it obviously has general utility for use in all applications. The contacts are 35 so arranged that the lamp is held securely in position in the lamp socket housing and excellent electrical contact is maintained between the lamp contacts and those of the lamp holder. Further, it is a relatively simple matter to mount the lamp in the socket, since the lamp prongs are 40 merely moved transversely into the recess and given a turn to lock the lamp in position.

Certain modifications can obviously be made in the construction shown, particularly in making the socket broadly universal. For instance, the base could extend in both directions from the vertical member 14 and the face of the vertical member altered to provide a through recess. Two cover plates would then be provided, one carrying the raised portions 18, 19, 20 and suitable openings for the contact prongs, and the other identical to plate 31. These plates would fit into suitable ledges formed in member 14 and be fastened together to form a unitary structure.

I claim:

1. A socket for fluorescent lamps having spaced contact pins comprising a body of insulating material having a generally arcuate recess, the center of said arcuate recess having an arcuate guide portion of a diameter equal to the spacing of said pins, a slot opening through a side wall of said body into said recess in line with a tangent of said guide portion remote from the end wall of said body, said tangent forming substantially a right angle with said side wall, and contact springs in said recess for detachably engaging said prongs.
2. In a socket for fluorescent lamps as in claim 1 wherein in two channels lead from said arcuate recess, said channels having means therein to hold said contact springs in said body.
3. In a socket for fluorescent lamps as in claim 1 wherein said arcuate recess is a C-shaped recess.
